UNITED STATES PATENT OFFICE.

JAMES STIMPSON, OF BALDWINSVILLE, MASSACHUSETTS.

IMPROVED CLAMP FOR WRINGING-MACHINES.

Specification forming part of Letters Patent No. **58,694**, dated October 9, 1866.

To all whom it may concern:

Be it known that I, JAMES STIMPSON, of Baldwinsville, in the county of Worcester and State of Massachusetts, have invented a new and Improved Clothes-Wringing Machine; and I do hereby declare that the following is a full, clear, and exact description of the same, reference being had to the accompanying drawings, making a part of this specification, in which—

Figure 1 is a front sectional view of my invention, taken in the line *x x*, Fig. 2; Fig. 2, a transverse vertical section of the same, taken in the line *y y*, Fig. 1.

Similar letters of reference indicate corresponding parts in the two figures.

The invention consists in an improved means for securing the machine to the box or tub, whereby the machine may be adjusted to tubs of different sizes or diameters, and having staves of different thicknesses, and also adjusted to boxes having sides of different thicknesses.

To enable others skilled in the art to fully understand and construct my invention, I will proceed to describe it.

A A represent the two end pieces of the frame of the wringing-machine. These end pieces are constructed of cast-iron, each piece A having a pendent bar, *a*, which forms its lower part, the upper parts, *b*, being of rectangular open or skeleton form, like a frame. The upper parts, *b*, have their sides and upper and lower ends of curved form transversely, the curved sides forming recesses *a**, to receive india-rubber springs B, two at each side or end piece.

The lower ends of the springs B are fitted in sockets *c* in cross-bars C, which are allowed to rise and fall freely in the recesses *a**, and the upper ends of said springs are fitted in caps or sockets *c*' in the under sides of cross-bars C', upon which set-screws D, which pass through the tops of the side pieces, A A, bear.

In the lower cross-bars C the journals *e* of the upper roller, E, are fitted, while the journals of the lower roller, E', are fitted in the lower ends of the upper parts, *b*, of the end pieces, A A, and are permanent.

The rollers E E' may be constructed in the usual, or in any proper way. What are termed

the "india-rubber rollers" will be most generally employed, as they have not, as yet, been superseded.

At one side of the upper parts, *b*, of the end pieces, A A, there are flanges, to which vertical wooden bars *g* are attached, and the two metallic end pieces, A A, are connected by wooden transverse bars F F, one of which has its ends fitted and secured in sockets *h* at the upper ends of the parts *b* of the end pieces, and the ends of the lower bar, F, are fitted and secured in sockets *h*' at the lower parts of *b*.

On the upper part of each pendent bar *a* of the end pieces, A A, there is fitted a horizontal bar, G, and these bars are allowed to turn freely on *a*, and have each a pendent rod, H, which rods are parallel with the bars *a*. The horizontal bars G are sustained in proper position on the bars *a* by means of lips or projections *i* on said bars, the bars having recesses made in them, so that they may be slipped down and off from the bars *a*.

Through the upper part of each pendent rod H there passes a horizontal screw, I, and the inner ends of these screws may be made to bear against the edges of sector-projections J at the lower ends of the parts *b* of the end pieces, A.

By this arrangement the rods H may be turned and secured in any position within the scope of nearly a quarter-circle, which is all that is necessary. This adjustment of the rods H admits of the machine being fitted to tubs of different diameters.

To the under side of each bar G there is attached a spring, K. These springs extend down at the inner side of each bar *a*, and set-screws L, which pass horizontally through the lower parts of the bars *a*, bear against these springs K, which prevent the tub or box being injured or marred by the ends of the set-screws.

The wooden bars *g* prevent the clothes, as they pass between the rollers E E', from coming in contact with the metallic end pieces, A A, while the transverse bars F F, which connect the end pieces, A A, being of wood, cannot, of course, soil the clothes. The springs B, in consequence of being fitted in caps or sockets in the cross-bars C C', as shown, are

firmly retained in proper position, being effectually prevented from turning outward or toward the rollers E E', as would otherwise be the case.

Having thus described my invention, what I claim as new, and desire to secure by Letters Patent, is—

1. The adjustable rods H, attached to or cast with horizontal bars G, which are fitted loosely on the pendent bars *a* of the end pieces, A, and provided with screws I to bear against

the edges of sector-projections J, for the purpose described.

2. The springs K, in combination with the adjustable rods H, set-screws L, and pendent bars *a*, arranged as and for the purpose set forth.

JAMES STIMPSON.
